UNITED STATES PATENT OFFICE.

OGDEN S. SELLS, OF BUFFALO, NEW YORK.

LABELING-MACHINE.

1,393,581.

Specification of Letters Patent. Patented Oct. 11, 1921.

Application filed June 28, 1920. Serial No. 392,205.

To all whom it may concern:

Be it known that I, OGDEN S. SELLS, a citizen of the United States, residing at Buffalo, in the county of Erie and State of New York, have invented new and useful Improvements in Labeling-Machines, of which the following is a specification.

This invention relates to a machine for applying labels on cans or packages which are filled with food products or similar goods and has for its object the provision of a machine whereby this purpose may be accomplished in a quick, reliable, economic and efficient manner.

In the accompanying drawings: Figure 1 is a side elevation, partly broken away, of a labeling machine embodying my invention. Fig. 2 is a top plan view of the same. Fig. 3 is a horizontal section taken on line 3—3, Fig. 1. Fig. 4 is a fragmentary top plan view of the machine, showing the manner of centering the cans on the conveyer. Fig. 5 is a rear end elevation of the machine. Fig. 6 is a vertical transverse section, on an enlarged scale, taken on line 6—6, Fig. 1, and showing the manner of applying a quantity of adhesive to the top of a can preparatory to depositing a label thereon. Fig. 7 is a fragmentary longitudinal sectional elevation of the upper part of the machine, on an enlarged scale, taken on line 7—7, Fig. 2. Figs. 8 and 9 are fragmentary vertical transverse sections, taken on the correspondingly numbered lines in Fig. 7. Fig. 10 is a plan view of a portion of the label strip from which the labels are formed. Fig. 11 is a horizontal section taken on line 11—11, Fig. 7. Fig. 12 is a sectional view showing a modified form of the strip feeding mechanism.

Similar characters of reference indicate corresponding parts throughout the several views.

In its general organization, the machine comprises means for depositing a quantity of liquid adhesive on each can, means for feeding a label strip, means for cutting labels successively from the label strip and pressing the same on the adhesive coated portion of the cans, and means for carrying the cans successively past said adhesive supplying device, label strip feeder, and label cutting and applying devices.

20 represents the main frame of the machine which may be of any suitable construc-

tion to support the various working parts of the machine.

The conveyer for the cans or packages to be labeled preferably comprises an endless chain belt 21 having an upper horizontal operative stretch and a lower horizontal idle stretch and front and rear turns which pass around front and rear sprocket wheels 22, 23. The latter are mounted on horizontal shafts 24, 25, respectively, which are journaled transversely in bearings on the main frame.

On the lower front part of the main frame is journaled a horizontal transverse driving shaft 26 which is provided at one end with a pulley 27 adapted to receive a driving belt. An intermittent forward movement is imparted to this chain belt from the uniformly turning driving shaft 26 journaled horizontally and transversely on the lower rear part of the main frame by means which preferably comprise a ratchet wheel 28 secured to the rear conveyer shaft 25, a ratchet lever 29 pivoted to turn about the axis of the ratchet wheel and provided with a pawl 30 engaging with said ratchet wheel and also provided with a longitudinal groove or channel 31, and a rotary crank arm 32 secured to the driving shaft and having a wrist pin or roller 33 which engages with the groove of the ratchet lever. By this means a continuous rotary motion of the crank arm 32 causes an oscillating movement of the ratchet lever whereby a step-by-step forward movement is imparted to the conveyer chain through the medium of the ratchet mechanism.

Inasmuch as the wrist of the crank gradually sweeps farther away from the axis of the ratchet lever during the forward stroke of the latter and gradually sweeps toward the axis of the same during the return stroke of the same, the ratchet lever moves comparatively slow while advancing the conveyer but relatively fast when the conveyer is at rest and also produces an easy starting and stopping action of the conveyer which reduces wear and jarring of the machine.

On its outer side the conveyer chain is provided at intervals with transverse conveyer wings or plates 34 which project laterally beyond opposite edges of this belt and also sufficiently close together lengthwise of this belt so that when the same are

on the straight upper and lower stretches of this belt the same form practically a continuous surface. The opposite ends of these conveyer plates while on the upper operative stretch of the conveyer slide on two horizontal longitudinal ways or tracks 35 mounted on the main frame and on the lower idle stretch of this conveyer belt these plates slide with their opposite ends on horizontal 10 longitudinal guideways or tracks 36.

The cans, packages or similar articles 37 which are to be labeled are placed by the attendant on the receiving or front portion of the operative stretch of the conveyer and 15 are then carried forward step by step to the devices which deposit a quantity of adhesive on the upper end of each can and then affix a label thereto. The present machine is 20 designed more particularly for labeling cans having cylindrical bodies and flat ends and each can is adapted to rest with its lower flat end on the conveyer plates and receive the label at its upper flat end. In order 25 to properly position the cans on the conveyer relatively to the adhesive or gum supplying and label affixing devices, centering means are provided comprising a plurality of pairs of centering pins 38 arranged at 30 intervals on the proper conveyer plates and on opposite sides of the path of the cans are arranged two longitudinal centering arms 39 of flexible material such as spring steel which are supported at their front ends by 35 posts 40 on the main frame and normally converge in the direction of movement of the cans and on opposite sides of the path of the same.

If the attendant places the can indiscriminately on the plates of the conveyer, 40 the latter will carry the same forward until it is engaged on its opposite sides by the centering arms 39 which latter then detain the can and cause the conveyer plates to slide past the underside of the same until 45 the centering pins 38 engage with the can and cause the latter to be moved forwardly positively. As the can is forced into engagement with both pins of a pair, the same is 50 also centered into the proper position to register with the gum supplying and label affixing devices which subsequently operate on the same.

41 represents an upright nozzle which is arranged above the path of the cans as the 55 latter are moved forward by the conveyer, this nozzle being adapted to deliver a quantity of liquid gum, paste, mucilage or similar adhesive upon the central part of the top of the can. Although various means 60 may be employed for supplying the liquid adhesive or gum to and discharging the same from the nozzle to the can top, those shown in the drawings are preferred and 65 comprise an upright pump having the outlet of its cylinder or barrel 42 at the lower end

thereof connected with the upper receiving end of the nozzle, a plunger or piston 43 reciprocating vertically in the pump barrel, a liquid adhesive supply tank or reservoir 44 mounted on the main frame and having 70 an outlet at its lower end which is connected by a delivery pipe 45 with the inlet of the pump, a forwardly-opening check valve 46 arranged between the outlet of the pump and the inlet of the nozzle, a forwardly-opening check valve 47 arranged in the pipe between the supply tank and the pump barrel, a vertically swinging operating lever 48 pivoted on the upper part of the main frame, an upright shifting rod 49 guided 80 on the rear part of the main frame and connected with the rear end of the operating lever 48, and an eccentric strap 50 surrounding an eccentric 51 on the main driving shaft and having a pitman 52 which is connected with the lower end of the shifting rod 49, as shown in Figs. 1, 2, 5, 6 and 7. The timing of the conveyer and the pump operating mechanism is such that while the can is being moved forward a step by the 90 conveyer after being placed thereon by the attendant, the plunger of the pump is raised or moved backwardly, thereby drawing a charge of liquid gum from the supply tank 95 into the pump barrel. When the can comes to rest underneath the gum delivery nozzle at the end of a forward step of the conveyer, then the plunger descends and ejects the liquid gum therein through the nozzle and upon the top of the can at the center thereof, this operation being repeated for each can 100 presented to the gum delivery mechanism.

After receiving the deposit of gum on its upper end the can is advanced another step by the conveyer and presented to the devices which affix a label 53 to the gummed surface. The labels for this purpose are preferably cut or stamped out from different sections of a strip, tape or band 54 of paper or other suitable material a supply of 105 which is arranged in the form of a roll 55 immediately in rear of the gum pump and nozzle and on which labels have been previously printed in a spaced relation lengthwise of the strip. The supply roll is mounted on a supply spool or reel 56 which is journaled loosely and removably on a spindle 57 secured at one end to the upper part of the main frame. From the supply reel the label strip passes downwardly and forwardly around a front guide roller 58 mounted on the adjacent part of the main frame, thence forwardly and horizontally lengthwise of the path of the can and immediately above the upper end of the same, 110 thence upwardly around a rear guide roller 59 pivoted on the adjacent part of the main frame and thence wound in the form of a roll 90 around a receiving reel or spool 60 arranged above the rear guide roller. The 115

label strip is fed forwardly intermittently, each step being equal to the distance between the labels printed or otherwise formed thereon. This strip feeding mechanism in 5 its preferred form comprises a feed roller 61 arranged horizontally and transversely above the part of the band or strip between the front and rear guide rollers and provided at its opposite ends with annular rows 10 of teeth 62 which engage with two longitudinal rows of openings 63 formed in the strip adjacent to its opposite edges, and thereby cause the strip to be positively moved forwardly when the feed roller is rotated. For the purpose of enabling the teeth 15 of the feed roller to remain in engagement with the holes of the strip and maintain a good grip thereon, a horizontal retaining plate 64 is mounted on the main frame in 20 position to support the strip on its underside immediately below the feed wheel, this plate being provided with clearance openings or slots 65 to permit the passage of the teeth of the feed roller. The latter is rotated 25 intermittently so that the label strip moves forwardly in unison with the can conveyer, this being preferably accomplished by securing the feed roller to one end of a feed shaft 91 which is journaled on the main 30 frame, a counter-shaft 66 journaled on the main frame and having a gear pinion 67 meshing with a gear wheel 68 on the conveyer shaft 25 and a chain belt 69 passing around a sprocket pinion 70 on the counter- 35 shaft and a sprocket wheel 71 on the feed roller shaft, as shown in Figs. 1, 2, 3 and 5. The receiving reel or take-up spool is driven frictionally so as to take up the waste rear part of the label strip or band from which 40 the labels have been cut and pressed on the can. This frictional drive, as shown in Figs. 2, 5 and 8, may consist of a round belt 72 passing around a grooved pulley 73 on the feed roller shaft and a grooved pulley 74 on a shaft 75 which is journaled on the main frame and to which the take-up 45 reel is detachably secured.

Between the label strip supply roll and the feed roller is arranged the device whereby 50 the labels are successively cut from the strip and pressed on the gummed surface of the can. In its preferred form the cutting device comprises a die plate 76 which supports the underside of the strip immediately in 55 rear of the front guide roller 58 and preferably is formed in one piece with the retaining or guide plate 64 and secured to the lower part of a bracket 77 which forms part of the main frame. This die plate is provided 60 with a vertical die opening 78 over which the label strip passes and below which each can comes to rest momentarily after a film of gum has been deposited thereon. The label strip is confined on the die plate over 65 the die opening therein by a guideway 79

formed in the underside of the bracket 77 above this opening. 80 represents a vertically reciprocating punch which is guided in ways 81, 82 on the bracket 77 in line with the die opening and connected at its upper end 70 with the operating lever.

While the strip of label material is advancing one step to present a new or fresh section of the same to the cutting position, and the conveyer is moving a can to the label 75 receiving position, the punch is elevated. When the conveyer and label strip come to rest at the end of a step, the can stands under the cutting mechanism and thereafter the punch descends and forms a label by 80 pushing that part of the strip above the die plate downwardly through the die opening therein and then directly depositing this severed label upon the surface of the can which has been previously coated with a film 85 of adhesive material, thereby causing the label to stick to the can. This cycle of operations is repeated for each label cut and affixed to the cans successively moved to the label receiving position by the conveyer. 90

The waste portions of the label strip containing the perforations 83 formed by the removal of the labels therefrom is taken up by the take-up reel in the same measure as the forming and affixing of the labels progresses. 95

After the labels have been affixed to the cans the same are advanced step-by-step until they reach the rear part of the upper stretch of the conveyer from which they 100 may be removed or discharged in any approved manner.

When the label strip has been exhausted, the reel 60 upon which the waste of the same has been wound, is removed and replaced by 105 the empty reel on the supply spindle 57, and another reel having a roll 55 of fresh label strip or tape is substituted for the reel 56. The supply of liquid adhesive may also be replenished from time to time as required 110 through the top of the reservoir which is normally covered by a lid.

Instead of feeding the label strip by means of a toothed feeding wheel, as shown in Figs. 7 and 8, this may be accomplished 115 instead by omitting the perforations in the tape or strip and feeding the same frictionally by engaging the opposite sides of the strip 84 by plain-faced feed rollers 85, 86, as shown in Fig. 12, to which rollers an intermittent forward rotary motion may be imparted by suitable means. 120

In the construction of the machine, the front side of the main frame is so constructed that it is comparatively open and permits of easy access to all parts of the machine for inspection, adjustment or repairs. 125

This method and apparatus for making and applying labels to cans and other ar- 130

ticles is not only very economical but it is also very expeditious and permits the packages to be properly labeled with a minimum waste of material.

5 I claim as my invention:

A labeling machine comprising a conveyor adapted to transport the articles to be labeled, means for depositing a quantity of adhesive on that part of each article intended to receive the label including a de-

livery nozzle arranged above the path of the articles, an adhesive reservoir, a pump cylinder having its inlet connected with said reservoir and its outlet connected with said nozzle, a plunger movable in said cylinder, 15 and a rock lever for operating said plunger, and means for delivering labels to the adhesive coated surface of said articles.

OGDEN S. SELLS.
